(57) **CLAIM**

We claim the ornamental design for a sign, as shown and described.

DESCRIPTION

FIG. 1 is a right front perspective view of the first embodiment of a sign showing our new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a right front perspective view of the second embodiment of a sign shown in a folded position; FIG. 9 is a front elevation view thereof, the rear elevation view being a mirror image thereof; FIG. 10 is a right side elevation view thereof, the left side elevation view being a mirror image thereof; FIG. 11 is a top plan view thereof; FIG. 12 is a bottom plan thereof; FIG. 13 is a right front perspective view of a sign shown in an open position; FIG. 14 is a front elevation view thereof, the rear elevation view being a mirror image thereof; FIG. 15 is a right side elevation view thereof, the left side elevation view being a mirror image thereof; FIG. 16 is a top plan view thereof; and, FIG. 17 is a bottom plan view thereof.

The broken line portion of the figure drawings is included to show portions of the article that form no part of the claimed design.

1 Claim, 14 Drawing Sheets
